UNITED STATES PATENT OFFICE.

OTTO K. CAZIN, OF NEWARK, NEW JERSEY.

GYROSCOPIC STEERING DEVICE.

1,189,239.

Specification of Letters Patent.

Patented July 4, 1916.

Application filed August 9, 1915. Serial No. 44,513.

To all whom it may concern:

Be it known that I, OTTO K. CAZIN, a citizen of the United States, residing at the city of Newark, in the county of Essex and State of New Jersey, have invented certain new and useful Improvements in Gyroscopic Steering Devices, of which the following is a specification.

My invention relates to improvements in the gyroscopic steering or guiding mechanism, for automobile torpedoes, and consists in the addition of a second gyroscope together with a proper mechanism for starting said second gyroscope at some predetermined time after the firing of the torpedo from the tube, and also for alining the said second gyroscope with the first gyroscope, so that the torpedo will continue on a straight course or turn to some predetermined angle at some fixed point in its course, said mechanism also to provide for the transferring of the steering function from the first gyroscope to said second gyroscope.

The objects of my improvements are, first—to cause the torpedo when fired at long range, to hold more truly to the line of aim than is possible with the present gyroscopic steering mechanisms, and, secondly—to provide a means for turning the torpedo through some predetermined angle at some predetermined point of its course.

It is a well known fact that the gyroscope when first fired and running at high speed will hold the torpedo true to the line of aim, but as the speed of the gyroscope wheel diminishes, it becomes less accurate in holding the torpedo to the true line. It is the object of the second gyroscope to start at high speed and take over the steering function when approximately half the range has been run and when the first gyroscope is approaching an unreliable speed; and by means of this transfer to carry the torpedo true to the mark. In extremely long range work, it would be possible by means of this mechanism to use any desired number of gyroscopes.

Gyroscopic steering devices as at present constructed allow the torpedo to be turned through some predetermining angle at the start of their run, but by means of the second gyroscope together with the starting and alining mechanism it is possible to turn the torpedo through a second predetermined angle at any desired point of its course. This function would be of value in firing at

the stern of a ship directly ahead, as the torpedo would not approach the ship in a direct line and through the water thrust from the ship's propellers but could approach at one side, and by turning the second angle at the proper time turn to attack the ship broadside on.

It is not my intention to claim any improvement in the gyroscope itself, my invention and improvement being applicable to gyroscopes of any practical design and spun by air or mechanical means.

The manner in which the desired objects are attained is shown in the accompanying drawing.

The figure is a sectional elevation of the steering mechanism in which A and B are gyroscopes of the air spun type in which a is the gyroscope wheel containing the buckets c^1 , and mounted in the inner gimbal ring b by the bearings b^1 , the inner gimbal ring being in turn mounted in the outer gimbal ring C by the bearings C^1 , the outer gimbal ring being held in the frame d by the bearings d^1 . The spinning nozzle is shown at d^2 and the seat and air connection at d^3 , and the locking lever at d^4 ; the tripper is shown at e, the plate at e^1 , with the reciprocating lever at e^2 , and its shaft and gear wheels at e^3 , e^4 and e^5 , the main torpedo driving shaft being e^6 . All these parts are made according to standard practice, and as no improvement is intended therein, a more detailed description of their functions is omitted.

The invention and improvement claimed consists in the addition of the gyroscope B together with the mechanism shown, in which f, f^1 , f^2 , f^3 and f^4 are in this case a train to gears driven from the main shaft. This train of gears is shown for convenience in the drawing, a longer train of gears being actually required and could consist of a combination of gears and worms and wheels, and driven from the main shaft or some other source of power, as for instance a clock spring. This gear train terminates in a rack or gear f^5 having a projection g arranged so that it can be moved with regard to f^5 so as to regulate the point at which the lever h will ride off the end of the projection g, and thus determine at what point of the course the gyroscope B shall start. The lever h swivels about the fixed shaft h^1 . The pin h^2 is attached to the lever h and passes through a hole in the gy-

roscope casing d . The hole h^3 in the outer gimbal ring C is placed so that when the axis of the gyroscope wheel is parallel to the longitudinal center line of the torpedo 5 then the hole h^3 and the pin h^2 will register. The lever h is drawn upward by the spring h^4 which holds the lever against the projection g and when the lever has fallen from the end of g the spring presses the pin h^2 10 lightly against the gimbal ring C until the hole h^3 comes into position when the pin enters the hole unless prevented from doing so by other actions which will presently be described. The lever h is also connected to 15 an air valve G in which g^1 is the piston and g^2 is the casing having the ports g^3 , g^4 and g^5 . The port g^3 is connected with the air supply and the port g^5 is connected to the spinning and unlocking mechanism of the 20 gyroscope B through the nozzle d^3 . The port g^4 is connected to the steering engine of the torpedo in such a manner that when the rudders are at one side of the torpedo the air pressure will be communicated 25 through the port g^4 onto the piston g^1 and will prevent the piston from rising under the influence of the spring h^4 , but if on the contrary the rudders are on the opposite side of the torpedo there will be no pressure 30 on the piston and the lever h will be free to rise and the pin h^2 can enter the hole h^3 when they come in line. The object of this regulation with regard to the rudder is that the pin h^2 can only enter the hole h^3 when 35 the torpedo is turning in one direction and the second gyroscope B can, therefore be set so as to compensate for the angle turned during the time it takes for the second gyroscope to be spun, and to take over the steering 40 function. When the pin h^2 has entered the hole h^3 the piston g^1 assumes a position such as to allow the air to pass from g^3 to g^5 and thus to spin the second gyroscope B and cause it to be unlocked and to take over 45 the steering function; the air pressure from g^5 at the same time passing to the second steering engine and also operating a valve cutting off the first steering engine.

The torpedo can, of course, be turned through any desired angle when the second 50 gyroscope is started, by the regular means as provided in the gyroscopes now in practical use.

The mechanism herein shown and described is suitable for a gyroscopic steering 55 mechanism by which a torpedo is guided straight on the line of aim of the launching-tube for its complete course or is turned through some predetermined angle at some predetermined point of its course. A 60 mechanism which will allow the torpedo to be turned through two angles, that is, one angle at the start of its run and one angle at some other predetermined point of its course, is the same in every respect except that the 65 pin h^2 passes through the top instead of the bottom of the gyroscope frame d and the hole h^3 is in the plate c^1 instead of in the outer gimbal ring c . The hole h^3 and the pin h^2 are so located that they will register 70 when the longitudinal center line of the torpedo is parallel to the line of aim.

I claim as my invention—

1. A gyroscopic steering mechanism comprising two or more gyroscopes and a mechanism to start said gyroscopes successively, substantially as hereinbefore described. 75

2. In a gyroscopic steering device, the combination of a gyroscope with a second gyroscope and a mechanism for starting said second gyroscope, said mechanism also alining the second gyroscope with the first gyroscope and transferring the steering function from the first gyroscope to the second gyroscope, all substantially as described 85 and for the purpose set forth.

3. In a gyroscopic steering mechanism, the combination of two or more gyroscopes and a mechanism for starting and alining successive gyroscopes and transferring the 90 steering function to successive gyroscopes, substantially as set forth.

OTTO K. CAZIN.
